his Attorney.

UNITED STATES PATENT OFFICE.

MICHAEL FRIAR, OF BLANCHARD, NORTH DAKOTA.

STORM SASH AND DOOR FASTENER.

1,295,725.

Specification of Letters Patent. Patented Feb. 25, 1919.

Application filed December 4, 1918. Serial No. 265,250.

To all whom it may concern:

Be it known that I, MICHAEL FRIAR, a citizen of the United States, residing at Blanchard, in the county of Traill and 5 State of North Dakota, have invented certain new and useful Improvements in Storm Sash and Door Fasteners; and I do hereby declare the following to be a full, clear, and exact description of the invention, such as 10 will enable others skilled in the art to which it appertains to make and use the same.

This invention relates to door and window sash fasteners, and more particularly to a fastener for storm windows, doors and 15 screens.

The object of the invention is to provide a simple, inexpensive and efficient device of the character referred to, specially designed and adapted for use in fastening storm windows, screens or doors, but capable of being 20 used for various other purposes.

The invention will first be described in connection with the accompanying drawings, which form a part of this specification; 25 and will then be pointed out in the claims at the end of the description.

In said drawings wherein I have illustrated a preferred form of embodiment of the invention applied to a storm window 30 sash:

Figure 1 is a front elevation of a window showing my improved fastener arranged to hold the storm window-sash firmly in place while permitting it to be easily adjusted or 35 removed;

Fig. 2 is an enlarged front view of the fastener, and

Fig. 3 is a sectional view taken on the line 3—3 of Fig. 2.

40 Referring to said drawings, in which the same reference letters are used to denote corresponding parts in different views, the letter A denotes a storm sash and B the casing or frame having my improved fastener applied thereto. In the form shown, the fastener consists essentially of a base plate C, having apertured lugs c rising therefrom, and a cam lever D, pivoted to and between 45 said lugs and having an eccentric head portion d arranged to bear upon a longitudi-

nally movable dog E, interposed between said base plate and lever with one end thereof extended so that it may overlap and engage the edge or margin of the storm sash, in the manner shown in the drawings, and 55 firmly secure the sash in place while permitting it to be readily adjusted or removed, if desired, by throwing the cam lever back into the dotted line position shown in Fig. 3 of the drawings, and sliding or drawing the 60 dog back so as to release the sash. The sliding dog may be conveniently secured to the base-plate with provision for adjustment by means of a bolt or screw passing through an oblong slot d¹ in the shank of the dog 65 and screwed into the casing or frame to which the sash is attached, and the projecting end of the dog is preferably formed with a lip or right-angled bend d² to take over the edge of the sash frame and prevent 70 sidewise movement.

I thus provide a very simple, inexpensive and efficient sash holder, which is adapted to be easily and quickly applied for holding a storm sash or screen, or analogous device in 75 place, adapting the sash to be easily adjusted and secured in different positions or removed, for storage during warm weather, or for other purposes.

Having thus described my invention, what 80 I claim as new and desire to secure by Letters Patent of the United States, is:—

1. A storm sash and door fastener comprising a base-plate for attachment to a window or door frame surrounding the sash, a 85 cam lever pivoted upon said base plate, and a longitudinally movable dog slidably confined between said base-plate and lever, said dog consisting of a substantially straight bar extending substantially parallel with 90 said base-plate and beyond the same at one end, said end being adapted to bear flat-wise upon the sash and to be pressed thereagainst by the cam so as to hold the sash firmly in place, substantially as described. 95

2. In a sash holder, a base plate having apertured lugs thereon, a lever having an eccentric head-portion at one end pivoted to and between said lugs, a longitudinally slideable dog interposed between said plate and 100

lever having one end extended beyond said pivot and having a longitudinally slotted shank to receive a bolt or screw for securing it to said plate, so as to permit longitudinal movement; the free end of said dog being adapted to bear upon the sash and to be pressed thereagainst by the cam so as to hold the sash firmly in place and having at

its end a lip or bend for engaging and preventing sidewise movement of the sash. 10

In testimony whereof I affix my signature in the presence of two witnesses.

MICHAEL FRIAR.

Witnesses:

W. T. CUMMINS,
IVOR SEINS.
